Primary Examiner — Kevin K Rudzinski*Assistant Examiner* — Clare Ann Gannon(74) *Attorney, Agent, or Firm* — Egbert Law Offices, PLLC(57) **CLAIM**

The ornamental design for a mat, as shown and described.

DESCRIPTION

FIG. 1 is an upper perspective view of a mat showing my new design.

FIG. 2 is front view thereof;

FIG. 3 is a rear view thereof;

FIG. 4 is a side view thereof;

FIG. 5 is an opposite side view thereof;

FIG. 6 is a top plan view thereof; and,

FIG. 7 is an enlarged detail view of area 7 in FIG. 6.

The bottom of the mat forms no part of the claimed design.

1 Claim, 2 Drawing Sheets(56)
